(57) **CLAIM**

The ornamental design for a gemstone arrangement, as shown and described.

DESCRIPTION

FIG. 1 is a top plan view of a gemstone arrangement according to my new design;

FIG. 2 is a front elevational view thereof;

FIG. 3 is a side elevational view thereof, the opposite side elevational view being a mirror image;

FIG. 4 is a rear elevational view thereof; and,

FIG. 5 is a bottom plan view thereof; and,

FIG. 6 is a perspective view thereof.

The dashed lines throughout the views are for environmental purposes only and form no part of this invention.
